UNITED STATES PATENT OFFICE.

WILLIAM C. JIRDINSTON, OF AUBURN, NEW YORK.

DESIGN FOR A BICYCLE-SUPPORT.

SPECIFICATION forming part of Design No. 27,310, dated July 6, 1897.

Application filed May 28, 1897. Serial No. 638,632. Term of patent 7 years.

To all whom it may concern:

Be it known that I, WILLIAM C. JIRDINSTON, a citizen of the United States, residing at Auburn, in the county of Cayuga and State 5 of New York, have invented and produced a new and original Design for a Bicycle-Support, of which the following is a specification, reference being had to the accompanying drawings, forming part thereof.

10 Figure 1 is a perspective view of a bicycle-support, showing my new design. Fig. 2 is an enlarged section on the line X X of Fig. 1.

The leading feature of my design consists 15 in the configuration produced by an inclined frame supported at a point intermediate its center and its forward end by a standard, both the frame and standard having a central portion cut away to admit and hold the periphery of a bicycle-wheel.

20 A is the inclined frame, of sufficient width to give it strength, its rear end resting upon the ground or floor. A slot B is formed in the frame and is smaller at each end than in the center, as shown.

The standard C is secured to the frame A 25 in any suitable manner and is of sufficient width at the bottom to insure steadiness of the entire design. The upper central portion of the standard is cut away to the same width as the widest portion of the slot B and diminishing approximately to the width of the ends 30 of said slot.

The entire design is graceful and pleasing and very useful for its purpose.

Having described my invention, what I 35 claim as new, and desire to secure by Letters Patent, is—

The design for a bicycle-support, substantially as herein shown and described.

In witness whereof I have hereunto set my 40 hand this 26th day of May, 1897.

WILLIAM C. JIRDINSTON.
